CLAIM

The ornamental Design for a tire sidewall, as shown and described.

DESCRIPTION

FIG. 1 is a perspective view of a tire sidewall showing our new design;

FIG. 2 is a front elevational view thereof;

FIG. 3 is an enlarged fragmentary perspective view thereof;
FIG. 4 is an enlarged fragmentary front elevational view thereof;

FIG. 5 is a perspective view of a second embodiment of a tire sidewall showing the opposite side of the tire sidewall of FIG. 1 with the tire of FIG. 1 rotated about a vertical axis 180 degrees;

FIG. 6 is a front elevational view of the second embodiment thereof;

FIG. 7 is an enlarged fragmentary perspective view of the second embodiment thereof; and,

FIG. 8 is an enlarged fragmentary front elevational view of the second embodiment thereof.

In the drawings, the broken lines showing of the tire tread, inner bead and the peripheral boundary between the tire tread and the sidewall in FIGS. 1 through 4 and 7 through 10 depict environmental subject matter and form no part of the claimed design.
